UNITED STATES PATENT OFFICE.

HORACE C. WILCOX, OF WEST MERIDEN, CONNECTICUT, ASSIGNOR TO THE MERIDEN BRITANNIA COMPANY, OF SAME PLACE.

DESIGN FOR A PRESERVE-DISH.

Specification forming part of Design No. 6,248, dated November 12, 1872.

To all whom it may concern:

Be it known that I, HORACE C. WILCOX, of West Meriden, in the county of New Haven, and State of Connecticut, have invented a new Design for Preserve-Dish; and I do hereby declare the following, when taken in connection with the accompanying drawing and the letters of reference marked thereon, to be a full, clear, and exact description of the same, and which said drawing constitutes part of this specification and represents, in—

Figure 1, a perspective view; and in Fig. 2, a longitudinal central section.

This invention relates to a design for the bowl of a preserve-dish, or what is sometimes called a berry-dish, to be usually supported upon a frame-work of plate; and it consists in the form of the bowl, made from glass, sub-

stantially as shown in the accompanying illustration, and as more fully hereinafter described.

The dish is of shell form, one end turning up and over, as shown in the illustration, and, made from glass, may be ornamented in any desirable manner, and by any of the processes known to manufacturers, the ornamentation forming no part of the design.

I claim as my invention—

The design for preserve-dish as herein described, and shown in the accompanying illustration.

HORACE C. WILCOX.
